ORNAMENTAL GATE STRUCTURES

Louis Blum, Pittsburgh, Pa.

Application October 18, 1956, Serial No. 616,793

1 Claim. (Cl. 39—87)

This invention relates to new and useful improvements in ornamental gate structures and it is among the objects thereof to provide a gate which shall be mounted on a hinge post and constructed in a manner to prevent sagging and distortion of the swinging gate portion and maintain alignment thereof with the ornamental rail structure with which it is associated.

The invention will become more apparent from a consideration of the accompanying drawings constituting a part hereof in which like reference characters designate like parts and in which:

Figure 1 is a front elevational view, partially cut away, of a gate post assembly embodying the principles of this invention;

Figure 2 is a top plan view, partially in section, taken along the line 2—2 of Figure 1;

Figure 3 is a similar view of a modified form of the device where the gate hinge post is supported by a wall;

Figure 4, a front elevational view of a gate post and rail assembly drawn to a reduced scale;

Figure 5, an isometric view of a hinge post and mounting;

Figure 6, a cross section taken along the line 6—6, Figure 4 drawn on an enlarged scale; and,

Figure 7, a cross-section taken along the line 7—7, Figure 4 drawn on an enlarged scale.

With reference to Figure 4 of the drawing, the numeral 1 designates an ornamental gate having a frame structure of the shape and design of an ornamental rail 2 and 3 which are supported independently of the gate. The gate 1 is mounted on a hinge post 4 that is pivotally supported on a pin 5 which is fastened to a base 6 secured by concrete as shown in Figure 4. The top of the hinge post 4 is pivotally mounted in a bracket 7 that is secured

2

to the ornamental rail 3 by a bolt 8 shown in dotted lines in Figure 1 of the drawing. The bracket 7 has a square sleeve 9, Figure 6, with a bearing 10 for receiving a pivot pin 11 which extends from the hinge post 4 in the manner shown in dotted lines in Figure 1 of the drawing.

The bottom of the hinge post 4 is provided with a supporting arm 12, Figure 5, with an offset portion 13 that has a concave face 14 complementary to the curvature of the bottom rail 15 of the gate 1. A lug 16 having threaded screws 17 extending therefrom fastens rail 15 of the gate in the manner shown in Figure 1, and the side rail 18 of the gate is similarly secured by screws 19 extending through spacing lugs 20 and 21, Figures 1, 4 and 5. As shown in Figure 2, the ornamental rails are of substantially elliptical shape and are provided with T-slots 2a for receiving channel shaped liners 2b for closing the slots. In Figure 3, the same type of mounting is employed for pivoting the post, but the connecting bracket 7 is attached to concrete by a screw 8 that passes into a threaded anchor 22 in a wall 22a.

The supporting arm 12 extending from the gate post 4 is an integral portion of the post 4, it being welded thereto as shown at 23, Figure 1, and the fastening of the gate rail structure to the post by the screws and spacing blocks provides a rugged construction which will not get out of shape. The large pivot bearings in the respective ends of post 4 provides effortless swinging action which eliminates binding and distortion of the gate and associated rail structures.

Although one embodiment of the invention has been herein illustrated and described, it will be evident to those skilled in the art that various modifications may be made in the details of construction without departing from the principles herein set forth.

35 I claim:

40 A gate comprising a support having an upright member provided with upper and lower pivot means, a laterally extending member operatively connected to said upright member adjacent the lower end thereof, and a substantially rectangular gate operatively connected to said upright portion at one end and to said laterally extending member at a bottom portion thereof.
